UNITED STATES PATENT OFFICE

ROBERT HARRIS, OF LONDON, ENGLAND, ASSIGNOR, BY MESNE ASSIGNMENTS, TO LITHOPRINTEX CORPORATION, A CORPORATION OF DELAWARE

DUPLICATING OR PRINTING APPARATUS

Application filed September 17, 1926, Serial No. 136,017, and in Great Britain September 25, 1925.

This invention is for improvements in or relating to duplicating or printing apparatus and particularly photographic step-and-repeat contact-printing machines. In such machines a frame for holding a unit, for example a photographic negative, to be brought into intimate contact with a press plate of zinc or aluminium, has been firmly secured face to face on a press member for pressing the unit on the press plate, but this arrangement did not provide for accommodating small differences in parallelism between the press member and the support for the press plate, or small differences in thickness of the order of 25/1000ths of an inch between different parts of the unit, such differences in thickness constituting, for example, a taper towards one side or towards a corner of the unit.

20 This invention has for its object to obviate this defect and to accommodate such differences in parallelism or thickness, so that pressure shall be applied as uniformly as possible over as large an area of the unit as possible.

According to a primary feature of the invention, there is provided in or for duplicating or printing apparatus, for example photographic step-and-repeat contact-printing apparatus, the combination with a press-member, and an unit-holding frame, of resilient suspension means for mounting the frame on the press-member in substantially parallel relation whilst permitting one part of the frame (e. g. one corner thereof) to approach nearer to or recede further from the press member than another part thereof, for the purpose of automatically accommodating 30 small inequalities in thickness either of the unit to be pressed, or the press plate against which the unit is to be pressed, and for accommodating small difference in parallelism between the pressing face of the press member and the support for the press plate.

According to another feature of the invention, the suspension means takes the form of a plurality of springs spaced apart around the frame, each of which springs is so connected to the frame and to the press mem-

ber as to constitute an "universal joint" connection.

Preferably, the springs are in the form of leaf springs and are firmly connected each at its ends to one of said members (for example the frame) and at its central portion to the other of said members (for example the press member) whereby there is provided an "universal joint" having a limited range of action.

One illustrative embodiment of the invention is illustrated by way of example in the accompanying drawings, wherein—

Figure 1 is a side elevation showing part of a press member and a press frame mounted thereon in accordance with the invention;

Figure 2 is a diagrammatic plan view of the press frame removed from the apparatus, and

Figures 3 and 4 are respectively a side elevation, partly in vertical section, and top plan view of one corner of the press member and press frame with the means connecting the same, but drawn to a scale larger than Figures 1 and 2.

Like reference characters designate like parts in all the views.

Referring to the drawings, a press member 10 movable towards and away from a fixed support 11 carries a rectangular press frame 80 designated generally by the numeral 12. This frame serves in known manner to carry an unit, such as a photographic negative, not shown, intended to be pressed against a plate, such as a sheet of zinc, or aluminium, 85 also not shown, resting against the support 11. It is very important that when the unit is a photographic negative it shall be pressed as uniformly as possible over its entire area against the press plate, and such uniformity of pressure is impaired if the thickness of either the unit or the press plate is not the same at one edge as it is at the opposite edge, or if the press member is not set parallel with the opposed face of the support.

In order to accommodate such irregularities the press frame 12 is suspended at its four corners by springs 13 from the press member 10. At each corner of the frame a leaf spring 13 is secured at its ends thereto

by bolts 14, whilst the middle portion of each leaf spring is bolted to the press member by a bolt 15 extending at right-angles to the leaf spring. Each of these resilient connections of the frame 12 to the press member 10 constitutes a kind of "universal joint" that has a limited range of action and permits any one corner of the frame to approach nearer to or recede further from the press member 10 and the support 11 than the other corners whilst preventing the frame from moving parallel to itself and laterally in relation to the press member 10. In this manner the small irregularities referred to above will be automatically accommodated, and the pressure will be distributed uniformly over the entire area of the unit.

Various modifications may be made in the details of construction described above without departing from the invention.

I claim:—

1. In photographic step-and-repeat contact-printing apparatus, the combination of a fixed support, a press member movable towards and away therefrom, leaf springs each connected at the middle of its length to said press member, and an unit-holding frame connected to the said springs at their ends, substantially as set forth.

2. In duplicating apparatus, the combination of an apertured press member, a unit-holding frame registering therewith, and a plurality of suspension means connecting said frame to said press member in substantially parallel relation thereto, which suspension means are resilient independently one of another each in a direction normal to the press member to permit not only slight bodily movement of the frame as a whole towards and away from the press member but also slight tilting movement of the frame, but are substantially rigid in a direction at right angles to that bodily movement to prevent the frame from moving parallel to itself and laterally in relation to the press member.

3. In duplicating apparatus, the combination of a unit-holding open frame through which light can pass, a fixed support, apertured press means registering with said frame for advancing the latter towards said support, and a plurality of means connecting said frame and support and permitting a tilting movement of said frame during said advancing movement, whilst preventing lateral movement thereof parallel to itself and laterally in relation to the said press means.

4. In photographic step-and-repeat contact-printing apparatus, the combination of an apertured press-member, a fixed support opposed thereto, an open unit-holding frame registering with the press member, and a plurality of springs connecting said frame to said press member at situations spaced apart in such manner as to permit a spring at one

of said situations to flex to an extent differ-

ing from that of the springs at the other situations, whereby the frame can tilt in relation to the press member.

In testimony whereof I affix my signature.

ROBERT HARRIS.
